UNITED STATES PATENT OFFICE.

ALBERT H. SAWYER, OF NORTH WEARE, NEW HAMPSHIRE.

SLEIGH.

SPECIFICATION forming part of Letters Patent No. 394,726, dated December 18, 1888.

Application filed September 15, 1888. Serial No. 285,474. (No model.)

To all whom it may concern:

Be it known that I, ALBERT H. SAWYER, of North Weare, in the county of Hillsborough and State of New Hampshire, have invented 5 certain new and useful Improvements in Sleighs and Sleds; and I do hereby declare the following to be a full, clear, and exact description of the invention, such as will enable others skilled in the art to which it appertains to make and use the same.

My invention relates to an improvement in sleighs and sleds, and particularly to a type in which springs are employed to obviate shock when the runners encounter obstructions or roughness on the road-bed that would 15 jolt the occupants of the sliding vehicle.

One object of my present invention is to provide a sleigh or sled with a simple and efficient spring compensating device which 20 will absorb the percussive action of the runner caused when moving rapidly over an uneven road-bed or when said runners ride up on snow-crust and break it down, and at the same time prevent lateral swaying motion of 25 the sleigh-body, the line of spring vibration being rendered vertical, or nearly so.

A further object is to furnish a spring compensating device for the prevention of shock or jolting percussion in a double-runner 30 sleigh or sled, spring mechanism being applied to both sets of runners and adapted to afford vertical yielding action thereto, while the front set of runners is allowed to swivel on a center plate laterally.

With these objects in view my invention 35 consists in certain features of construction and combinations of parts, which will be hereinafter set forth, and indicated in the claims.

Referring to the drawings making a part of 40 this specification, Figure 1 is a side elevation in perspective of a sleigh to which the improved spring appliance is attached. Fig. 2 is a top plan view of the running-gears of a sleigh, showing the method of constructing my improved spring device and its application to a 45 sleigh having one pair of runners. Fig. 3 is a rear elevation of the mechanism shown in Fig. 2. Fig. 4 is a side elevation of a double-seated sleigh having two sets of spring shock-absorbing appliances attached thereto. Fig. 5 50 is a cross-section of a sleigh-body with modified form of the spring shock-absorber adapted for

heavy loads. Fig. 6 is a side elevation of a bob sleigh or sled having two pairs of runners, which are supplied with my improved spring 55 shock-absorbers, the front pair of runners being swivel-connected to the body. Fig. 7 is a transverse elevation of the sleigh-gears shown in Fig. 3, with the torsion-springs removed and the parts enlarged to clearly illustrate the manner of constructing the details. Figs. 8 and 9 are detached views of important 60 details enlarged.

D is the body of the sleigh. (See Fig. 1.) This may be given any desired degree of finish and variation in design to suit the taste of the builder. It is provided with a strong light frame having three parallel pieces, D', (shown in dotted lines in Fig. 2,) that extend longitudinally to afford means for securing 65 the bottom boards, and also for proper stable attachment of the sleigh-body upon its running-gears. The latter-named parts consist of a pair of runners, C, given the form substantially as shown, although this shape may 70 be varied at will of the constructor.

On the runners C the elliptical plate-springs B are mounted. These may have any required number of leaves so disposed and secured upon each other as to produce elastic 75 springs of proper strength and resilience for the load they are to sustain.

The springs B are hinged to the rear ends of the runners C, as shown, and swung in loops, or are hinged at their forward ends to 80 said runners, the curvature of the plate-springs B being such with regard to that of the runners and the forward points of hinged connection of the same that a portion of the bodies of the springs B will lie in nearly a 85 horizontal plane and approximately parallel to the tread or bearing-surface of the runners.

The body D is secured in place upon the springs B by the bent metallic bolster-plates G, 90 which have their outer ends fastened upon the springs in any improved manner and their inwardly-extended portions similarly attached to the three frame-bars D', as shown in Fig. 2, the bars being represented in dotted 95 lines.

Across the front of the runners B a cross-bar, E, is pivoted on the projecting studs E', so as to hold the runners and permit them to 100

have an independent vertical movement. On this bar E the thills F are hinged or shackled in the usual manner.

Upon bolster-plates G the transverse shafts 5 a are held to rock by the loop - bolts v, which pass upwardly through the longitudinal frame-pieces D' and are secured thereto by nuts. The shafts a, extending in the same axial line, have their inner ends supported in 10 contact with each other by said bolts, which are preferably located between pairs of spaced collars a³, as shown in Fig. 7, so that end-thrust of both shafts will be prevented.

On the ends of the rock-shafts a, inside of 15 the loop-bolts v, the arms a' are integrally formed, these, bending downwardly and outwardly a proper distance, terminate in cylindrical bosses a², which are perforated in a line parallel with the axis of the shafts, and 20 check-shoulders T are provided, that depend from the bosses a² on each side of the joint, to prevent too great a flexing action of the joints.

The knee-pieces A are bifurcated at their 25 upper ends to produce spaced parallel ears e on each, as shown in Fig. 3, these ears being perforated to be pivoted to the bosses a² of the arms a', and thus afford hinged joints to these pieces that are adapted to permit the 30 knee-pieces to vibrate in line with the runners, but prevent any deflection of the joined pieces laterally, the lower end of the knee-pieces A being clipped to the runners C at II, so as to afford hinged joints which will coact 35 with the upper joints, a², and thus permit a rocking vibration of the shafts a, arms a', and knee-pieces A in an obvious manner.

There are two torsional wire springs, S, spirally wound upon the inner ends of the 40 shafts a, which springs have their outer terminals engaged with the ears i and their other ends in bearing-contact with the center longitudinal frame-piece D', as shown in Fig. 3. The direction of the coils of the springs 45 S is such that their strength will be exerted to lift and transfer the weight of the knee-pieces A upon the plate-springs B, thus rendering the action of these parts more sensitive under light loads, so that percussive action incidental to abrupt contact of the runners with inequalities of the road-bed will be quickly neutralized.

In Figs. 4 and 5 are shown a modified form of the running-gears substantially like that 55 just described, but so changed as to render the same capable of sustaining heavier loads; and to this end two sets of compensating mechanism are provided to aid in elastically supporting the body of a two-seated sleigh.

60 It will be seen in Fig. 5 that the duplicate rock-shafts a have the spiral coiled springs S, located near the arms a', the inner terminals of said coils engaging the perforated ears i and their other ends bearing upon the outer longitudinal frame-pieces D', so that the torsional resistance of the springs will be exerted nearer the knuckle-joints between the arms a' and

the knee-pieces A. By coiling the springs S more or less their force may be increased to a certain limit, and as the direction of these 70 coils is reversed from those shown in Fig. 3 their strength will be added to that of the plate-springs B to sustain weight placed in the body D of the sleigh, and these will coact to absorb any jolting of the sleigh which 75 may be occasioned by the movement of the runners over inequalities on the surface of the road-bed or the encounter of the runners with a mass of snow slightly incrusted that raises the front of the sleigh and permits it 80 to suddenly fall by reason of the breaking of this crust.

It is necessary that the strength of the springs S be proportioned to the capacity of 85 the vehicle to render them efficient in operation, and also the load-sustaining capacity of the elliptical plate-springs B, which are secured by the metal bolster-plate G to the 90 sleigh-body near the center of length of said springs and body.

The connection of the transverse rock-shafts a and spiral springs S is made to the front and rear of the bolster-plate, so as to spread 95 them and afford proper support to the weight placed on the front and rear seats when the 100 sleigh is in use.

In Fig. 6 the combined torsional and plate spring shock-arresting device is shown as applied to a bob sleigh or sled, two independent pairs of runners being employed to properly 100 sustain the long body D, and, as will be observed, the rear "bob" or pair of runners is connected to the body D by a bolster-plate, G, the depending ends of which are bent into flanges o, that are bolted upon the elliptical 105 plate-springs B. Any other preferred form of this bolster may be utilized to secure the springs B in alignment with the sides of the body D, the ends of the springs being shackled or otherwise connected to have hinged joints 110 with the runners C at or near their front and rear ends, as shown.

The arrangement of the rock - shafts a, springs S, and jointed knee-pieces A, together with the integral arms a', on the rear bob is 115 substantially shown in Fig. 5, this form of connection of the parts being preferred as best adapted to support heavy loads.

The front bob or the sled shown in Fig. 6 is provided with a wooden or metal bolster, m, 120 that is secured on the plate-springs B, the wedge-shaped end blocks, n, being introduced between the lower surface of the bolster and the springs B to sustain the upper surface of the bolster in a plane about parallel with the 125 tread or wearing-face of the runners C.

A longitudinal groove is cut in the lower surface of the bolster m to receive the rock-shafts a, which are similar in form to those shown in Fig. 5. The shafts may be secured 130 to the bolster by loop-bolts, as previously described, or metal boxes of ordinary form may be secured to the lower side of the bolster m to afford rocking support to the shafts a.

Upon the under side of the body D, near the forward end, as shown, the center plate, P, is attached by the connected diagonal braces O q, which may be of any preferred form to adapt them to the purpose of affording a rigid support to the center plate, P, which has swivel-connection with the bolster m to permit the forward bob to be turned on the plate as a center, in the usual way.

All of the knee-pieces A have been shown as inclining forwardly to flex toward the front of the sleigh or sled. This is not absolutely necessary, as it is apparent that equally as good results will be obtained if the joints moved toward the heels of the runners C.

As shown in Figs. 3 and 5, the knee-pieces A have their outer faces nearly in the same vertical plane with the runners C. This is preferred, as it relieves the joints a^2 of lateral strain, but it is not imperative that such a form of construction should be resorted to, for if there is a considerable degree of inward inclination given to the knee-pieces A and joints a^2 these joints will flex and the yielding support of the springs S be rendered available.

If preferred, the rock-shafts a may be made continuous as one shaft and the rock-arms a' be made separate and secured upon the shaft in line with each other after the springs S have been placed on the shaft, and connected therewith in the same manner as previously shown, or one spiral spring of proper length and strength may be substituted for two separated springs.

Minor changes of construction of the parts of this device might be made without departing from the spirit or exceeding the scope of my invention; hence I do not desire to limit the construction of parts or their combinations to the exact form and arrangement herein shown; but,

Having fully described my invention, what I claim as new, and desire to secure by Letters Patent, is—

1. The combination, with a body, a rock-shaft, arms for the rock-shaft, and a spring secured to the shaft and engaging the body, of runners and a device to maintain the body and runners in vertical yielding connection and prevent lateral motion of the body, substantially as set forth.

2. The combination, with a body, two rock-shafts having arms on their outer ends, and

two torsional springs, of a pair of runners, springs secured at their ends to the runners, 55 and a yielding device adapted to hold the body from side motion and permit a vertical reciprocation of said body, substantially as set forth.

3. The combination, with a body, a transverse bolster, runners, and two plate-springs secured to the runners, of a rock-shaft having arms located in the same plane and adapted to be hinged to two knee-pieces, a spiral spring located on the rock-shaft, and two knee-pieces 65 jointed to the rock-arms and runners, having flexible joints that yield only in line with the runners, substantially as set forth.

4. The combination, with a body, a bolster, a pair of runners, and plate-springs hinged to 70 the runners, of two rock-shafts located in axial alignment and connected to the under side of the body so as to rock, spiral springs secured to and mounted on the rock-shafts, two rock-arms on the ends of the rock-shafts, and knee-pieces hinged to the rock-arms and runners and adapted to prevent any lateral motion of the body and permit free vertical reciprocation of said body, substantially as set forth.

5. The combination, with a sled-body provided with two independent sets of runners, 80 of rock-shafts, springs thereon, rock-arms, springs connecting the body and runners, and knee-pieces hinged to the rock-arms and runners, the forward set of runners being provided with a swiveling device to permit it to swing laterally, substantially as set forth.

6. The combination, with a sleigh or sled body, two independent sets of runners, plate-springs bowed and hinged by their ends to 90 the runners, and a bolster-plate for the rear set of runners, of rock-shafts for each set of runners, rock-arms on these shafts, springs that are mounted on the shafts and connected to the knee-pieces, hinged to the rock-arms and 95 the runners, and a swiveling device for the front pair of runners, substantially as set forth.

In testimony whereof I have signed this specification in the presence of two subscribing witnesses.

ALBERT H. SAWYER.
